UNITED STATES PATENT OFFICE.

DANIEL J. CLARK, OF JERSEY CITY, NEW JERSEY, ASSIGNOR TO
HILLIARY ELDRIDGE AND JAMES C. YOUNG, OF JERSEY CITY,
NEW JERSEY.

MANTLE-HANGER.

No. 807,061.

Specification of Letters Patent.

Patented Dec. 12, 1905.

Application filed June 14, 1905. Serial No. 265,163.

To all whom it may concern:

Be it known that I, DANIEL J. CLARK, a citizen of the United States, and a resident of Jersey City, in the county of Hudson and State of New Jersey, have invented certain new and useful Improvements in Mantle-Hangers, of which the following is a specification.

My invention relates to mantle-hangers. 10 It has for its object to provide a mantle-hanger comprising a plurality of independent curved sections or frames placed together to form a ring, each section adapted to support an independent hollow section of a ring-like mantle, whereby if one section of the mantle becomes burned out or broken it may be removed and replaced by a new one.

It has for a further object to provide a hanger of the character set forth embodying 20 advantages in point of simplicity and inexpensiveness of construction and effectiveness in use.

In the drawings, Figure 1 is a sectional view showing my hanger supporting a mantle on a burner. Fig. 2 is a perspective view 25 of the hanger. Fig. 3 is a perspective view of a modified form of the hanger.

In all the figures of the drawings illustrating my invention like reference characters 30 designate corresponding parts.

Referring to Figs. 1 and 2 of the drawings, 1 designates a burner-head connected with the gas-supply by a pipe 2 and comprising a casting embodying a central chamber 3, a reticulated cap 4 thereon, and downwardly-extending radiating burners 5, leading from the chamber 3. To provide means for supporting a mantle-hanger and mantle, to be hereinafter described, in the proper relation to 35 the burners, bosses 6 are formed on the burners, and each is provided with a vertical bore 7, intersected by a horizontal screw-threaded bore 8, engaged by a set-screw 9. A globe 10, open at the top and closed at the bottom, 40 is supported on the supply-pipe, so as to surround the burner, mantle, and hanger.

The hanger comprises independent curved frames 15 and 16, each formed of a single piece of wire or other suitable material bent 45 to present a horizontal portion 17, having large openings 18, 19, and 20, connected by narrow passages 21 and 22, and a vertically-extending portion 23, adapted to be inserted

into one of the bores 7 in the burner and be secured therein by the set-screw 9. These 55 hangers are for the purpose of supporting an incandescent mantle comprising independent hollow sections 25 and 26, having pockets connected by narrow passages.

Referring now to the modification shown 60 by Fig. 3 of the drawings, this form of hanger comprises independent frames 30 and 31, each formed of a single piece of wire or other suitable material bent to present a horizontal portion 32, having a substantially semicircular opening 33 and a vertically-extending portion 35, adapted to engage one of the bores 7 and be secured by the set-screw 9. The incandescent mantle 40 supported by 65 this form of hanger comprises independent hollow substantially semicircular sections 41 and 42.

These mantles are not herein claimed, as 70 they form the subject of an application which I have filed concurrently herewith.

I do not wish to be understood as limiting myself to the precise details and arrangements of parts shown and described, but reserve the right to all modifications within 75 the scope of my invention.

Having now described my invention, what I claim as new, and desire to secure by Letters Patent, is—

1. A hanger for incandescent mantles, 80 consisting of independent frames inclosing a space, each frame having an opening adapted to receive a plurality of burners, substantially as described.

2. A hanger for incandescent mantles, 85 consisting of independent frames inclosing a space, each frame having an opening adapted to receive a plurality of burners and means for supporting it on a burner, substantially as described.

3. A hanger for incandescent mantles, 90 consisting of independent irregularly-curved frames inclosing a space, each frame having an opening adapted to receive a plurality of burners, substantially as described.

Signed at New York, in the county of New 95 York and State of New York, this 15th day of May, A. D. 1905.

DANIEL J. CLARK.
